ATTORNEY

UNITED STATES PATENT OFFICE.

ALLEN H. MIDDLESWART, OF PIQUA, OHIO.

CHECK PROTECTOR.

Application filed December 19, 1924. Serial No. 756,914.

To all whom it may concern:

Be it known that I, ALLEN H. MIDDLESWART, a citizen of the United States, residing at Piqua, in the county of Miami and State of Ohio, have invented certain new and useful Improvements in Check Protectors; and I do hereby declare the following to be a full, clear, and exact description of the invention, such as will enable others skilled in the art to which it appertains to make and use the same.

This invention relates to check perforating devices and has for its object to provide a device of this character simple in construction and less costly to manufacture than those heretofore proposed.

With these and other objects in view the invention resides in the novel details of construction and combinations of parts more fully hereinafter disclosed and particularly pointed out in the claims.

Referring to the drawings forming a part of this specification in which like numerals designate like parts in all the views,

Figure 1 is a top plan view of the invention;

Figure 2 is a sectional view taken on the line 2—2 of Figure 1 and looking in the direction of the arrows;

Figure 3 is a partial elevational view of a detail of construction; and

Figure 4 is an enlarged detailed sectional view taken on the line 4—4 of Figure 1.

This device consists of an upper die plate 1, a lower die plate 2 and a base plate 3 suitably secured together at their central portions as by the rivet 4 provided with the squared shank 5 adapted to snugly fit a centrally disposed square hole in each of the plates 1, 2 and 3 to prevent the rotary motion of the same, and the whole secured tightly together by heading the rivet as indicated at 6.

The upper die plate 1 is provided centrally with the depression 10 having the flat face 11 adapted to contact with the upper surface of the lower die plate 2 adjacent thereto. The depression 10 is also provided with the annular shoulder 12 and the web portion 13 adapted to normally lie in a plane substantially parallel to the plane of the depressed portion 10. At the extremity of the web portion 13 and as indicated at 14 the upper die plate or disk 1 is provided with a plurality of integral radial

arms or die members 15 at the outer extremities of each of which is provided a suitable die member which may be as in this case a figure or a character. These radial die members 15, see Figure 2, are normally inclined upwardly from the extremity 14 of the webs 13.

The lower die member or disk 2 is of a diameter slightly larger than the diameter taken through two oppositely disposed die members 15 and is suitably attached as by the screws 16 to the outer circumference of the base member 3. Directly beneath the die members 15 and adapted to register accurately with the figures or characters carried by said die member, is a complementary die portion 20. The base member 3 has cut out portions 21 underlying the die portions 20 of the lower die disk 2.

The dies located at the outer extremity of each radial die member 15 are formed in a suitable press by forcing the metal of the member 15 about two-thirds the way through the thickness of the said member. That is to say, the metal of the arm or die member 15 is forced out of the plane of the arm 15 to provide the outstanding pegs or portions 25 approximately circular in cross section and provided with a flat face 26 substantially parallel to the surface 27 of the arm 15 from which said peg extends. This of course leaves on the upper surface of the arm 15 corresponding depressions such as indicated at 28 the arrangement of which, with respect to each other, constitutes the outline of the figure or character desired. With reference to Figure 1 it will be observed that the depressions 28 in one instance form the outline of the numeral or figure 1 while in another instance, as seen in the same figure, the depressions 28 form the outline of the figure 2, and it will be understood from the foregoing that immediately underneath the depressions 28 are corresponding pegs 25 on the under side of the arms 15.

The die members 20 located in the lower die disk 2 are provided with perforations 30 of the same size as the pegs 25 and with which they coact, when the extremity of the arm 15 is brought down in the direction indicated by the arrow, see Figure 4.

The operation of the device is as follows: A check 35 or any other suitable paper to be perforated is inserted between the upper

radial arms 15 and the lower die member 2. The extremity of the desired radial arm 15 is then depressed whereupon the pegs 25 carried thereby in their endeavor to go 5 through the opening 30 of the lower member 2 will shear or cut from the said check 35 that portion of the check lying between said pegs 25 and said perforations 30, all in the usual and well known manner. The 10 radial arms are inclined upwardly as above disclosed to provide a spring action by means of which the arms 15 are returned after functioning to the positions shown in Figure 2. That is to say, when the arm 15 is depressed, or moved toward the base of the device, the same will pivot about the shoulder 12 as a center until the lower portion 36 of the web 13 contacts with the upper surface of the lower die plate 2, whereupon 15 the point 36 will then become the pivot during the continued downward movement of the arm 15. This subsequent downward movement is opposed by the web 13 being rigid or integral with the central portion 10 of the upper plate which is in turn securely fastened as by the rivet 4 to the base member 3. Therefore upon the release of downward pressure on the arm 15 the same will 20 return to normal or elevated position. Also, due to the construction and disposition of parts of the arm 15 the pegs 25 of said arm will shear the check 35 at the same moment. This is due to the fact that the lower surfaces 26 of the pegs are in a plane parallel 25 to the plane of the under surface 27 of the arm 15, and when the arm 15 is depressed the plane thereof will approach parallelism with the plane of the lower die plate 2.

In order that the check 35 will not hang 30 on the pegs 25 after the check has been perforated and the pressure on the arm 15 released there are provided strippers 40. These strippers are formed when the upper die plate 1 is stamped from sheet metal by 35 shearing the metal along the line 41 thereby producing one side edge of the stripper 40 as well as a side of the radial arm 15, the stripper 40 being fastened at its innermost extremity to the web 13. The plate 1 during this stamping operation is subsequently 40 pressed to give the upward inclination to the radial arms 15 and a downward curve to each of the strippers 40. It will thus be noticed from the drawings that when the parts are assembled the strippers are normally 45 in pressed contact with the upper surface of the lower die plate 2, but when a check indicated at 35 is inserted between the stripper 40 and the die plate 2 the stripper is raised and due to its spring action holds the check 35 tightly against the die plate 2. Upon the operation of the arm 15 to 50 perforate the check and its subsequent release the strippers 40 located on either side of the arm 15 will hold the check 35 to the

lower plate 2 thus stripping the check from the pegs 25 of the arm 15. There are provided a pair of strippers as clearly shown in Figure 1 for each of the die arms 15 in order that the check may be suitably held 70 on both sides of the die.

In order that the very small pieces or disks of paper cut from the check 35, upon the actuation of the proper die arms 15 may not escape from the device there is provided 75 on the under side of the base member 3 a relatively stiff disk of paper or other suitable material 45 suitably attached as by paste or glue to the central portion of the said base member 3. This disk of paper 45 is provided at its circumference with a dished or upturned unattached portion 46 adapted to contact with the under side of the base member 3. By this means the tiny 80 disks of cut paper are collected in the pocket formed by the cutaway portion 21 of the base member 3 and the unpasted portion of the paper 45 extending from its circumference 46 to such a point as indicated at 47 in Figure 2. After the device has been in use 85 for some time the tiny disks of paper above mentioned may be removed from the device by running the blade of a pen knife or some other suitable object between the circumferential edge 46 of the paper 45 and the base member 3 while holding the device in a plane approximately vertical. In this manner the cut pieces of paper, which are 90 so objectionable because of the inability to gather the same up from any object, are collected or retained and disposed of at a later time in a suitable receptacle.

From the foregoing it will thus be seen that there is provided a check perforating device having an upper plate which is formed from a single piece of sheet material. Further it will be observed that each stripper 40 is formed by shearing, as along the line 41, a strip from a side of each arm 15 leaving the stripper thus formed integrally 105 attached to the web 13. It will also be seen that the strippers 40 are then pressed into such shape as to provide a spring tension, when the parts are assembled, thus holding 110 a check 35 against the lower plate 2.

The arms 15 are pressed into such shape as to provide a similar spring tension, and due to the web portion 13 being above the plane of the central portion 10, the arms 15 will move downwardly until the circular bent portions 36 come into contact with plate 2 whereupon said bent portions 36 will act as fulcrums for said arms 15. This allows said arms 15 to be first placed under a slight tension and then under a stronger tension. This second or stronger tension will thus insure the return of the arm 15 and its associated projections 25 to a position amply sufficient to allow the subsequent insertion 125 of a check 35.

It is obvious that those skilled in the art may vary the details of construction as well as the combination of parts without departing from the spirit of the invention; therefore it is not desired to be limited to the foregoing except as may be demanded by the claims.

What is claimed is:

1. In a check protecting device the combination of an upper plate provided with a depressed central portion and integral radial arms extending outwardly and upwardly; a plurality of projections disposed near the extremity of each arm; a lower plate 10 contacting with the central portion of said upper plate and provided with a plurality of perforations adapted to register and coact with the projections of each of said arms to cut disks of paper from a check interposed 15 between said upper and lower plates; means to hold said interposed check in contact with said lower plate during the operation of the device; a base member; means to secure together said upper plate, said lower plate and said base member in fixed rigid and unrotatable relation to each other; and means associated with said base member to receive the said disks of paper.
2. In a check protecting device the combination of an upper plate provided with a 20 depressed central portion, a web portion, and integral radial arms extending outwardly and upwardly from said web portion; a plurality of integral projections disposed near 25 the extremity of each arm, the bottom faces of said projections lying in a plane parallel to said arm; a lower plate contacting with the central portion of said upper plate and provided with a plurality of perforations 30 adapted to register and coact with the projections of each of said arms to cut disks of paper from a check interposed between said upper and lower plates; means to hold said interposed check in contact with said lower plate during the 35 operation of the device; a base member; means to secure together said upper plate, said lower plate and said base member in fixed rigid and unrotatable relation to each other; and means associated with said base member to receive the said disks of paper.
3. In a check protecting device the combination of an upper plate provided with a 40 depressed central portion and integral radial arms extending outwardly and upwardly; a plurality of projections disposed near 45 the extremity of each arm; a lower plate contacting with the central portion of said upper plate and provided with a plurality of perforations 50 adapted to register and coact with the projections of each of said arms to cut disks of paper from a check interposed between said upper and lower plates; means to hold said interposed check in contact with said lower plate during the operation of the device; a base member; means to secure together said upper plate, said lower plate and said base member in fixed rigid and unrotatable relation to each other; and means associated with said base member to receive the said disks of paper.
4. In a check protecting device the combination of an upper plate provided with a 55 depressed central portion, a web portion, and integral radial arms extending outwardly and upwardly; a plurality of projections disposed near 60 the extremity of each arm; a lower plate contacting with the central portion of said upper plate and provided with a plurality of perforations 65 adapted to register and coact with the projections of each of said arms to cut disks of paper from a check interposed between said upper and lower plates; means comprising a pair of resilient strippers associated with each arm and integral with said web portion to hold said interposed check in contact with said lower plate during the 70 operation of the device; a base member; means to secure together said upper plate, said lower plate and said base member in fixed rigid and unrotatable relation to each other; and means associated with said base member to receive the said disks of paper.
5. In a check protecting device the combination of an upper plate provided with a 75 depressed central portion and integral radial arms extending outwardly and upwardly; a plurality of projections disposed near 80 the extremity of each arm; a lower plate contacting with the central portion of said upper plate and provided with a plurality of perforations adapted to register and coact with the projections of each of said arms to cut disks of paper from a check interposed between said upper and lower plates; means comprising a pair of resilient strippers associated with each arm and integral with said web portion to hold said interposed check in contact with said lower plate during the 85 operation of the device; a base member; means to secure together said upper plate, said lower plate and said base member in fixed rigid and unrotatable relation to each other; and means associated with said base member to receive the said disks of paper.
6. A check protecting device comprising an upper member provided with a plurality of radially extending arms each provided near its extremity with a number of projecting pegs, said arms inclined upwardly and outwardly from a depressed central portion contacting with a lower member provided with a number of perforations 90 adapted to register with said pegs and co-

acting therewith to cut disks of paper from the check interposed between said upper and lower members, strippers associated with each arm to remove from said pegs 5 the check after the same has been cut, a base member to which said upper and lower members are rigidly and unrotatably attached, said base member provided with a cutaway portion associated with each of 10 said arms and adapted to receive the disks cut from said check, and a disk of paper attached to the central portion of said base member and provided with an unattached upturned edge contacting with the under 15 surface of said base member, said disk of paper forming with each of said cutaway portions a plurality of pockets to retain said cut disks in said device.

7. In a check protecting device the combination of an upper plate provided with a 20 depressed central portion and integral radial spring like arms extending outwardly

and upwardly, each arm provided with a bent portion adapted to act as a fulcrum when depressed; a plurality of projections 25 disposed near the extremity of each arm; a lower plate contacting with the central portion of said upper plate and provided with a plurality of perforations adapted to register and coat with the projections of each 30 of said arms to cut disks of paper from a check interposed between said upper and lower plates; means to hold said interposed check in contact with said lower plate during the operation of the device; a base 35 member; means to secure together said upper plate, said lower plate and said base member in fixed rigid and unrotatable relation to each other; and means associated with said base member to receive the said 40 disks of paper.

In testimony whereof I affix my signature.

ALLEN H. MIDDLESWART.
